(57) **CLAIM**

We claim the ornamental design for a magnetic disc storage unit for electronic computer, as shown and described.

DESCRIPTION

FIG. 1 is a front, top and left side perspective view of a magnetic disc storage unit for electronic computer showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is an enlarged perspective view of the portion identified in FIG. 2 by the section "B-B" and "C-C", shown separately to more clearly illustrate the gridded portions.

The broken line showings of the portions in FIG. 5 are included for the purpose of illustrating unclaimed portions of the magnetic disc storage unit for electronic computer and the dash-dot lines represent the bounds of the claimed design; all broken lines form no part of the claimed design.
